UNITED STATES PATENT OFFICE.

HENRY L. PITMAN, OF WESTFIELD, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed February 27, 1923. Serial No. 621,520.

To all whom it may concern:

Be it known that I, HENRY L. PITMAN, a citizen of the United States, residing in Westfield, in the county of Union and State of New Jersey, have invented certain new and useful Improvements in Typewriting Machines, of which the following is a specification.

This invention relates to machines for writing bills for telephone service, in which operation it is required to type, in separate columns, the date, the number of messages, the place called, the company's charge, the United States tax and a code symbol. The principal object of the invention is to provide means for expediting writing of these bills, and particularly to expedite the movement of the carriage to the tax and code columns by causing it to jump automatically to each of these columns upon the completion of the entry in the preceding column. The invention is useful for other purposes, however.

The typewriter-carriage is propelled in letter-feeding direction by the usual spring drum, and is controlled by suitable escapement mechanism comprising a pinion, in mesh with a rack having teeth at letter-space intervals, on the carriage. The carriage is jumped automatically to the tax column without attention from the operator upon the completion of the entry in the preceding column of the bill by omitting from the rack the teeth, which would ordinarily connect the carriage with the escapement mechanism to control the letter-feeding movement of the carriage between these columns. The carriage, being unrestrained when this gap is reached, is caused to jump forward and is arrested by engagement of the escapement pinion with the next tooth on the rack, which thus positions the carriage for writing in the tax column.

The amount of the tax item is always either five or ten cents. Two special keys are provided, one for writing "05", and the other for writing "10" in the tax column, so that the tax is always written by a single key-stroke. It is desired to cause the carriage to jump automatically to the code column as an incident of the writing in the tax column. The pinion always has two teeth in positions to be engaged by the rack and is advanced a single tooth-space at each

operation, so that each pinion tooth has two rack-engaging positions. Two feeding steps are ordinarily required, therefore, to move a rack-tooth past the escapement pinion. In order to advance the carriage as desired, it is necessary to get the rack tooth which arrests the carriage in the tax column past the pinion at a single writing operation. For this purpose a cam is provided on the rack in position to be engaged and lifted by a rack-lifting roller forming part of the tabulating mechanism, as the carriage is advanced under the influence of the escapement mechanism due to the tax writing operation. This lifts the rack momentarily out of engagement with the escapement pinion, releasing the carriage to the action of the spring drum. When the rack descends, the pinion is opposite a second gap in the rack, so that the carriage continues to advance until arrested by a rack-tooth at the opposite side of this second gap. A single key is then operated to write the code symbol. The carriage is returned by a motor automatically set into operation at the end of each line; that is, by the writing of the code symbol.

One feature of the invention relates to the arrangement of the carriage-returning motor and the connections between it and the carriage, with reference to the machine. These parts are mounted upon the rear of the machine-frame and project but slightly to the rear of it. The motor and the carriage-operating connections are made in two separable units, each removably mounted on the back of the machine-frame. Each of these units comprises a shaft, and these shafts are substantially aligned and are loosely connected when operatively positioned, with provision for universal movement. Such provision makes it unnecessary to align the shafts accurately when mounting the units upon the machine.

Another feature of the invention is the modification of the tabulating frame of the machine to give clearance for the passage of the motor-connections. The pivot-shaft of the tabulating frame is divided, and its sections are connected by a member, at one side of them, which surrounds and is braced by the rod on which the tabulating stops are mounted. A shaft, driven by the motor,

passes through the opening thus formed in the tabulator-frame shaft.

Another feature of the invention is the provision of improved mechanism for automatically line-spacing the platen, as an incident of its return movement. A carriage-returning rack on the carriage is movable relatively to the carriage for a limited distance, and during this relative movement 10 the rack operates a slotted crank to draw rearward a vertical pin on the line-spacing slide, and through said pin to line-space the platen. The connection between the slotted crank and the vertical pin is loose to permit vertical movement of the pin independently of the crank in case-shifting, and the pin is of such length that the connection between the line-spacing slide and the crank is not affected by such shifting. 15 20 Other features and advantages will hereinafter appear.

In the accompanying drawings,

Figure 1 is a rear elevation of the machine with parts broken away for clearness of 25 illustration.

Figure 2 is a fragmentary sectional side elevation, showing parts of the tabulating and escapement mechanisms.

Figure 3 is a fragmentary rear elevation 30 of the tabulator frame, showing how provision is made for the passage of the motor connection.

Figure 4 is a portion of a telephone bill written by the machine.

35 Figure 5 is a fragmentary side elevation, showing the platen-carriage shifted for upper-case writing.

Figure 6 is a side elevation of the escapement mechanism.

40 Figure 7 is a vertical longitudinal sectional view of a typewriting machine having the present improvements applied thereto.

45 Figure 8 is a fragmentary perspective view, showing particularly the automatic line-spacing mechanism.

Figure 9 is a fragmentary rear sectional elevation, showing the escapement mechanism and the rack in the relative positions 50 occupied just prior to writing the units digit in the company's charge column, when a single key-stroke will be effective to cause the carriage to jump to the tax column.

55 Figure 10 is a view, similar to Figure 9, showing the rack and pinion in the positions occupied when the carriage is in the tax column.

60 Figure 11 is a view, similar to Figure 9, showing the rack and pinion in the positions occupied just after the tax item has been written, the rack having advanced about one tooth-space from the position of Figure 10, and being lifted out of engagement with the pinion.

65 Figure 12 is a view, similar to Figure 9,

showing the rack returned to lowered position but still not engaged by the pinion due to the second gap in the rack-teeth.

Figure 13 is a view, similar to Figure 9, showing the rack in the position occupied 70 when the carriage is arrested in position for writing in the code column.

Figure 14 is a fragmentary plan view of the left end of the machine, showing the line-spacing mechanism. 75

Figure 15 is a fragmentary vertical longitudinal sectional view, showing the line-spacing mechanism.

Figure 16 is a fragmentary plan view of the left end of the machine, with parts 80 broken away for clearness of illustration.

A platen 10 is rotatably mounted in a carriage 11, which is supported on a front rail 12 and a rear rail 13, and urged in a letter-feeding direction by means of a strap 14 connected at one end to the carriage 11 and at the other end to a spring drum 15. Movement of the carriage 11 under the urging of the spring drum 15 is controlled by suitable escapement mechanism, comprising a rack 16 connected, with the carriage to travel therewith and meshing with a pinion 17 having a one-way connection through a pawl 18 with an escapement wheel 19, which, in turn, is controlled by fast and loose dogs 20 and 21, respectively, operated by a universal bar 22 in the paths of type-bars 23.

Depression of a palm tabulator (not shown) acts through a link 24 and an arm 25 to rock a column stop frame 26 about a shaft 27 to bring a column stop 28 operatively positioned on the frame 26 into the path of a stop 29 mounted on the typewriter-carriage 11. At the same time an arm 30 secured to the shaft 27 will be swung downwardly to 100 actuate a lever 31 about its pivot, to cause a roller 32 at the forward end thereof to lift the rack 16 out of engagement with the pinion 17, thereby releasing the carriage 11, and permitting it to be drawn by the spring drum 15 in letter-feeding direction until the counter-stop 29 on the carriage is moved into engagement with the next operatively positioned stop 28. The mechanism just described is, in general, similar to that disclosed in the patent to H. Crutchley, No. 929,080, dated July 27, 1909. 110

115 The machine comprises the usual number and alphabet keys 33, and, in addition, a special key 34 marked "Single tax" for writing "05," and a special key 35 marked "Double tax" for writing "10." As has been stated, the bills which the machine is designed to write comprise separate columns for the amount of the company's charge, the United States tax, and a code symbol (see Figure 4), and it is desired to cause the carriage to move to each of the latter columns automatically, upon the completion of the writing in the preceding column. To this 120 125 130

end, the teeth are omitted from the rack-bar 16 which would ordinarily control the letter-feeding of the carriage between the company's charge column and the tax column, leaving a gap 37 in the rack. When the carriage has reached the position for typing a units digit in the company's charge column, the rack and pinion will be in the relative positions shown in Figure 9, with only the 10 rack-tooth 36 in engagement with the pinion 17, it being engaged and detained by the pinion-tooth 41. The operation of a key 33 to write, advances the escapement-pinion 17 one tooth-space, withdrawing the tooth 41 15 from the path of rack-tooth 36. The carriage is thus left unrestrained, and, as it passes forward out of the charge column, it continues to advance until the tooth 38 at the opposite side of the gap 37 engages a tooth 20 43 of the pinion, as seen in Figure 10. The carriage 11 is correctly positioned for writing in the tax column when so arrested.

One of the special tax keys is operated to write the tax item, and its operation causes 25 the pinion 17 to be advanced one tooth-space, that is, moves the tooth 43 from its Figure 10 position to its Figure 11 position. In order to cause the rack-tooth 38 to clear the pinion 17 in this operation, so that the 30 carriage 11 may be jumped automatically to the code column, a staple-like member 45 is arranged to embrace the rack 16, with its lower leg 46 extending forward beyond the teeth of the rack in position to engage the 35 roller 32 and act as a cam to lift the rack 16 momentarily out of engagement with the pinion 17. This cam 46 rides up on the roller 32 as the Figure 11 position is reached, and thereby disengages the teeth 38 and 43 40 to release the carriage to the action of the spring-drum 15. As the carriage 11 moves forward, the rack 16 quickly descends (see Figure 12), but a second gap 39 in the rack permits the carriage to continue its advance 45 until arrested by engagement of the pinion-tooth 44 with the rack-tooth 40, as seen in Figure 13. This positions the carriage for writing in the code column.

The carriage is automatically returned to 50 the beginning of a new line immediately after the writing of the code symbol, there being provided, for this purpose, motor-controlling means similar to that disclosed 55 in the patent to F. A. Hart, No. 1,238,908, dated September 4, 1917. A link 47 is automatically thrust downward as the carriage 11 is letter-spaced, following the writing in the code column, and, through a rocking lever 48 pivoted on the machine-frame 49, lifts a slide 50 out of engagement with a locking plate 51. The slide 50 is drawn rearward by a spring 52 when lifted, and through an arm 53 rocks a shaft 54. The 60 rocking of the shaft 54, through suitable 65 connections for the purpose, closes a switch to start the motor 55 and simultaneously connects the motor to a pinion 56 meshing with a carriage-returning rack 57 on the carriage. The motor 55 and its connections are made in separable, removable units, all 70 of which are mounted on the back of the machine-frame 49, in positions such that the height of the machine is not increased by the addition of these parts. The motor 55 is mounted on a bracket 55^a, detachably 75 secured by screws 55^b, or other suitable means, upon the back of the machine-frame 49. The electrical conductors 55^c, which connect the motor with the motor-switch, terminate in a block 55^d, which is also removably secured upon the back of the machine-frame. The motor-shaft 58 has fixed upon it a sleeve 59 having slots 60 at its outer end. A second shaft 61, substantially 80 in alignment with the motor-shaft 58, has its end loosely received in the bore of the sleeve 59, and carries pins or lugs 62 which are engaged loosely in the slots 60 forming a universal connection therewith, to drive the shaft 61. It will be seen that the motor 85 with its shaft forms a readily removable and replaceable unit. A worm 63 on the shaft 61 drives a gear 64 on a clutch-member 64^a fixed on a shaft 65. The worm 63 and gear 64 are mounted in a suitable housing 64^c, carried on a bracket 64^b, removably secured upon the back of the machine-frame 49. The housing may be partially filled with oil to lubricate the worm 63 and gear 64. The housing and its connected parts 90 may be readily removed as a unit, for the purpose of making repairs. The pinion 56 is formed to co-operate with the fixed clutch-member and is connected to the motor 55 by 95 sliding it along the shaft 65 to engage it 100 with the fixed clutch-member 64^a.

The shaft 27 of the tabulator-frame 26 is divided, as seen in Figure 3, to permit the clutch-member 64^a to pass through. The sections of the shaft 27 are rigidly connected by a bar 66, which surrounds a rod 67 of the tabulator-frame. A carriage-returning key 68 is provided for use when no entry is to be made in the code column, or in the tax and code columns. This key, 110 when actuated, swings a bell-crank 69 to lift the slide 50 out of engagement with the locking plate 51.

The rack 57, with which the pinion meshes, is supported on guides 70, carried 120 by brackets 71 on the carriage 11. The guides 70 are received in horizontal slots 72 formed in the rack 57, the slots being of sufficient length to permit limited movement of the rack 57 relatively to the carriage 11. Headed screws 73, engaging the rear face of the rack 57 and attached to the guides 70, retain the rack 57 in position on the guides 70. When the movement of the 125 rack 57 by the motor is initiated, the rack 130

moves relatively to the carriage until the guides 70 engage the ends of the slots 72 in the rack, after which the rack and carriage move in unison. During the period 5 when the rack 57 is moving relatively to the carriage 11, the platen 10 is automatically line-spaced. The manual line-spacing mechanism, which is, in general, similar to the usual line-spacing mechanism of the Underwood typewriter, comprises a line-spacing lever 74, a slide 75, a pawl 76 carried by the slide 75, a ratchet-wheel 77 fixed on the platen-shaft 78 for operation by the pawl 76, and a spring 79 for returning the slide 10 75 to normal position. In accordance with the present invention, the slide 75 is provided with a rearward extension 80, which carries, at its rear end, a pin 81 extending vertically downward. This pin 81 is loosely 15 embraced by a slotted crank 82 on a vertical rock-shaft 83, which is mounted on a lateral extension 84 of the bracket 71 at the left end of the carriage 11. The shaft 83 has a second crank 85 at its lower end, 20 which plays in a recess 86 in the lower face of the rack 57. While the rack 57 is being moved relatively to the carriage 11 by the motor 55, the crank 85 is moved by the rack to rock the shaft 83 clockwise. The crank 25 82 is thus caused to draw the line-spacing slide 75 to the rear to line-space the platen 10. The loose connection between the crank 82 and vertical pin 81 permits the platen 10 to be shifted for upper-case writing (see 30 Figure 2), without affecting the connection of the line-spacing slide 75 with the carriage-return rack 57.

As the carriage is nearing the completion 35 of its return movement, the right marginal stop is effective through suitable connections, comprising a link 86, to open the motor-switch and disconnect the motor 55 from the carriage-returning rack 57, as set forth in the patent to Hart, previously referred to.

As soon as the rack 57 is disconnected, the 40 spring 79 draws the line-spacing slide 75 forward to its normal position, and the slide 75, through the described connections with the rack 57, moves the rack 57 toward the right, as seen in Figure 1, relatively to the carriage 45 11. It will be seen that the operator may line-space the platform 10 at will, through the operation of the line-spacing lever 74.

A chute 87, having right and left lateral 50 edge gages 88 and 89, is mounted on the usual paper-shelf 90 for guiding the bills to the platform 10, with their columns correctly positioned to receive the appropriate entries.

In using the machine, a bill is guided to 55 writing position by means of the chute 87, and the date, number of messages, place called, and company's charge entries are made, the machine being moved, from column to column, by operation of the usual 60 tabulating mechanism. Upon the completion of the entry in the company's charge column, the carriage jumps automatically two extra letter-spaces to the tax column. One of the special tax keys is operated to 65 write the tax item, whereupon the carriage jumps automatically two extra letter-spaces to the code column. A key is operated to write the code symbol, and this automatically causes the return of the carriage and 70 the line-spacing of the platen for the beginning of a new line. Should there be no occasion to make an entry in the tax column in a line, the carriage may be quickly moved to the code column by simply operating the 75 space-bar, and, should there be no entry for either the tax or code column, the carriage may be returned by operation of the carriage-return key 68. At the end of each bill, the total amount of the tax items is 80 written in the company's charge column, and the total amount of the bill is written below this. The platen may be line-spaced without returning the carriage, to position the bill for the writing of these items, by manual 85 operation of the line-spacing lever.

Variations may be resorted to within the scope of the invention, and portions of the improvements may be used without others.

Having thus described my invention, I 90 claim:

1. In a typewriting machine, the combination of a power-driven carriage, carriage-feed elements including a rack and a pinion, tabulating-carriage-releasing means to separate the rack and the pinion and release the carriage for a free movement to a column-stop position, and means secured to the rack engageable with the tabulating-carriage-releasing means whereby the carriage will be 100 automatically released and arrested within a predetermined zone during the normal operation of typing.
2. In a typewriting machine, the combination of a power-driven carriage, a carriage-feed mechanism including a feed-rack and a rack-holding pinion, tabulating-carriage-releasing mechanism including means to free the rack from the pinion and release the carriage for a free movement to a column-stop position, and an obstruction secured to the rack and arranged to ride over the rack-releasing means whereby the carriage will be 110 automatically released and arrested within a predetermined zone during the normal operation of typing.
3. In a typewriting machine, the combination of a power-driven carriage and a platen, typing elements, carriage-feed elements including a rack and a pinion, tabulating-carriage-releasing means to separate the rack from the pinion to release the carriage for a column-skipping movement, and camming means secured to the rack and movable therewith to engage with the tabulating-carriage- 120 125 130

releasing means whereby the carriage will be automatically released to skip a predetermined zone of two letter-space distances during the normal operation of typing.

5 4. In a typewriting machine for writing bills comprising a series of columns, an intermediate column of which includes only items written by a single key-stroke, a carriage, carriage-propelling means, escapement mechanism controlling the movement of the carriage, comprising a pinion, a rack on the carriage normally in mesh with two teeth of the pinion, said rack having a gap to permit the carriage to jump automatically to 10 said intermediate column upon the completion of the writing in the preceding column, a tooth on the rack for arresting the carriage in the intermediate column, said tooth being followed by a second gap, and means 15 for automatically lifting the rack out of engagement with the pinion as an incident of the writing in the intermediate column, to permit the tooth to clear the pinion at a single operation and thereby enable the carriage to jump automatically to the succeeding column.

5. In a typewriting machine for writing bills comprising a series of columns, an intermediate column of which includes only 20 items written by a single key-stroke, a carriage, carriage-propelling means, escapement mechanism controlling the movement of the carriage, comprising a pinion, a rack having gaps therein for causing the carriage to 25 jump to the intermediate column and the following column automatically, a single tooth on the rack between said gaps for positioning the carriage in the intermediate column, tabulating mechanism comprising a 30 member in engagement with the rack for lifting the rack out of engagement with the pinion at the will of the operator, and a cam on the rack positioned to engage said member and automatically lift the rack as an 35 incident of the writing in the intermediate column, to enable the carriage to jump to the succeeding column.

6. In a typewriting machine for writing bills comprising a series of columns, an intermediate column of which includes only 40 items written by a single key-stroke, a carriage, carriage-propelling means, escapement mechanism controlling the movement of the carriage, comprising a pinion, a rack 45 having gaps therein for causing the carriage to jump to the intermediate column and the following column automatically, a single tooth on the rack between said gaps for positioning the carriage in the intermediate 50 column, tabulating mechanism comprising a member in engagement with the rack for lifting the rack out of engagement with the pinion at the will of the operator, and means 55 for causing said member to lift the rack out 60 of engagement with the pinion automatically

as an incident of the writing in the intermediate column, to enable the carriage to jump to the succeeding column.

7. In a typewriting machine for writing bills comprising a series of columns, a carriage, carriage-propelling means, escapement mechanism for controlling the movement of the carriage, tabulating mechanism operable at the will of the operator for disconnecting the carriage from the escapement mechanism to permit the carriage to be jumped directly to a desired column, and means on the carriage, automatically moved by the tabulating mechanism at a predetermined point, to cause the carriage to be automatically jumped to a succeeding column.

8. In a typewriting machine for writing bills comprising a series of columns, a carriage, carriage-propelling means, escapement mechanism for controlling the movement of the carriage, tabulating mechanism operable at the will of the operator to disconnect the carriage from the escapement mechanism to cause the carriage to be jumped directly to a desired location, and means for causing the carriage to be automatically disconnected from the escapement mechanism by the tabulating mechanism at a predetermined point.

9. In a typewriting machine, a carriage, carriage-propelling means, escapement mechanism comprising a pinion movable step by step to control the letter-feeding movements of the carriage, a rack normally in mesh with said pinion, and means for automatically lifting the rack out of engagement with the pinion to initiate a space-jumping movement of the carriage, said rack having a gap in its teeth to continue the space-jumping movement.

10. In a typewriting machine, a carriage, carriage-propelling means, escapement mechanism for controlling the movement of the carriage, a rack having teeth normally in engagement with the escapement mechanism, and means, comprising members relatively movable under the control of the escapement mechanism, for moving the rack automatically beyond the reach of the escapement mechanism to initiate a space-jumping movement of the carriage, said rack having a gap in its teeth located to continue the space-jumping movement after the rack has been restored to normal position.

11. In a typewriting machine, a carriage, carriage-propelling means, a rack on the carriage having its teeth arranged at letter-space intervals, and escapement mechanism comprising a pinion having its teeth at letter-space intervals, and arranged to be advanced a tooth-space at each operation, each tooth of the pinion having two rack-engaging positions, the rack having a plurality of gaps in its teeth of unequal extent, for causing the carriage to jump forward

automatically, the arrangement being such that, at one of said gaps, the rack leaves engagement with one tooth of the pinion, and is arrested by engagement with the next pinion-tooth but one to the tooth last engaged, whereby the length of said jump is one tooth-space less than the number of teeth omitted from the rack.

12. In a typewriting machine, a carriage, carriage-propelling means, escapement mechanism comprising a pinion for controlling the movement of the carriage, and a rack on the carriage having teeth arranged at letter-space intervals, and normally engaging two teeth of the pinion for restraining the carriage by engagement with the pinion, said rack having a plurality of gaps for causing the carriage to jump automatically, one of said gaps co-operating with the pinion to cause a jump of a predetermined extent, and the other gap being of less extent, and co-operating with a cam to cause a jump of equal extent.

13. In a typewriting machine, a carriage, carriage-propelling means, escapement mechanism, a rack having its teeth arranged at letter-space intervals, connecting the carriage and the escapement mechanism, said rack having a plurality of gaps in its teeth to cause the carriage to jump forward automatically at predetermined points in its travel, and means for causing the ratio of the extent of the jump at the first gap to the extent of said gap to be different from the ratio of the extent of the jump at the second gap to the extent of the second gap.

14. In a typewriting machine, a carriage, carriage-propelling means, escapement mechanism controlling the movement of the carriage, a rack having teeth at letter-space intervals, in engagement with the escapement mechanism, said rack having a plurality of gaps of unequal extent between its teeth, and means for causing the carriage to jump equal distances at said gaps.

15. In a typewriting machine, a carriage, carriage-propelling means, a rack on the carriage having teeth at letter-space intervals, escapement mechanism for controlling the movements of the carriage, comprising a pinion having two teeth always in position to be engaged by the rack, said rack having two gaps in its teeth of unequal extent, for causing the carriage to jump automatically, and means for causing said jumps to be of equal length.

16. In a typewriting machine, a carriage, carriage-propelling means, a rack on the carriage having teeth at letter-space intervals, escapement mechanism for controlling the movements of the carriage, comprising a

pinion having two teeth always in position to be engaged by the rack, said rack having two gaps in its teeth of unequal extent, for causing the carriage to jump automatically, the first of said jumps being unequal in extent to the extent of the gap in the rack which controls it, and means for causing the other jump to be equal in extent to the extent of the gap in the rack which controls it.

17. In a typewriting machine, a carriage, carriage-propelling means, a rack on the carriage having its teeth arranged at letter-space intervals, escapement mechanism comprising a pinion having its teeth at letter-space intervals, and arranged to be advanced a tooth-space at each operation, each tooth of the pinion having two rack-engaging positions, the rack having a gap in its teeth for causing the carriage to jump forward as the pinion-tooth which engages the last rack-tooth in advance of the gap moves from its second rack-engaging position, a tooth on the rack at the opposite side of the gap for arresting the jump of the carriage by engaging the next tooth but one of the pinion to that last engaged, and means for automatically disengaging said last-mentioned rack and pinion teeth as said pinion-tooth moves from the first to the second rack-engaging position.

18. In a typewriting machine, a carriage, carriage-propelling means, escapement mechanism, a bar having rack teeth connecting it to the escapement mechanism, a rack-lifting member engaging with the bar, and a rack-disengaging device carried by the rack and bar and engageable with the rack-lifting member to cam the rack teeth free of the escapement mechanism.

19. In a typewriting machine, a carriage, carriage-propelling means, escapement mechanism, a rack having teeth connecting it to the escapement mechanism, a rack-disengaging device positioned on the rack between two of its teeth, and having a portion projecting beyond said teeth, and a rack-lifting member for engaging said projecting portion of the disengaging device to disengage the rack from the escapement mechanism.

20. In a typewriting machine, a carriage, carriage-propelling means, escapement mechanism, a rack having teeth connecting it to the escapement mechanism, a rack-lift roller, and means on the rack for automatically riding over said roller to disengage the rack and escapement mechanism to control the duration of such disengagement and cause the carriage to jump a predetermined distance.

HENRY L. PITMAN.
